UNITED STATES PATENT OFFICE.

PETER A. CARLSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

REMOVABLE TENSION ON NARROW-WARE SHUTTLE.

Application filed January 28, 1925. Serial No. 5,359.

This invention relates to improvements in shuttles for narrow ware looms and more particularly to tension devices therefor.

It is the general object of my invention to provide a removable tension for shuttles of the type mentioned to the end that the friction elements can be replaced quickly without disfiguring the shuttle.

It is a further object of my invention to provide tension elements mounted on a removable carrier and held in place by a tension spring in such a manner as to permit the removal of the holding means without disturbing the elements and their carrier, the spring acting to hold the parts in assembled position independently of the holding screws.

It is a still further and more detailed object of my invention to provide a tension for narrow ware shuttles wherein all of the parts which contact with the yarn may be formed of porcelain, the movable porcelain blocks being replaceable on a removable stand of stronger material which is held out of contact with the yarn.

With these and other objects in view which will appear as the description proceeds, my invention resides in the combination and arrangement of parts hereinafter described and set forth in the claims.

In the accompanying drawings wherein I have shown two forms of my invention,

Fig. 1 is a top plan view of a narrow ware shuttle having my invention applied thereto, certain parts being shown in section,

Fig. 2 is a front elevation of the shuttle looking in the direction of arrow 2, Fig. 1,

Fig. 3 is an enlarged section on line 3—3 of Fig. 2,

Fig. 4 is a section on line 4—4 of Fig. 3,

Fig. 5 is a fragmentary enlarged front elevation of a shuttle having a modified form of my invention applied thereto, and

Fig. 6 is a section on line 6—6 of Fig. 5.

In carrying out my invention I provide a shuttle 10 having a cop receiving slot 11 at one end of which is located an eye 12 formed of porcelain or other suitable material communicating with the slot and extending through the body of the shuttle. A second or intermediate eye 13 extends through the front wall 14 of the shuttle and communicates with a chamber 15 in which is located the tension device forming the subject mat-

ter of my present invention. A third or delivery eye 16 is located in the central portion of the forward wall 14, and the eyes 12, 13 and 16 are disposed substantially in alignment to have threaded through them the weft W as indicated in Fig. 1. A screw 17 extends from the wall 14 into the body 10 of the shuttle and has threaded thereon a pair of nuts 18 and 19, respectively, between which extends one end of a spring 20 the free end of which extends toward the other end of the chamber 15 and is held normally raised by the inclined position of the screw 17. By adjusting nuts 18 and 19 it is possible to vary the position and tension of the spring 20. The matter thus far described is of the usual construction and forms no part of my present invention.

My invention relates more particularly to the tension blocks which engage that portion of the weft W lying between eyes 13 and 16. In carrying out the preferred form of my invention I provide the rear face of the front wall 14 with a shallow slot 30 which receives the base 31 of a carrier indicated generally at 32. Said base has a tapped hole 33 therein which receives screw 34 extending through the wall 14. Secured to the base 31 are pins 35 which are parallel and of sufficient length to extend to the rear of chamber 15. Loosely mounted on said pins 35 are front and rear friction blocks or elements 36 and 37, respectively, which have holes 38 formed therein slightly larger than the pins 35. Spring 20 extends behind tension element 37 and serves to hold both of said elements forward. The pins 35 position the spring 20 and by lying in substantial contact with the rear wall of chamber 15 prevent accidental displacement of said spring.

It is found in practice that the blocks 36 and 37, which are usually formed of porcelain, are subject to frequent breakage, necessitating renewal. Heretofore said blocks have been mounted on pins which were fixed in the shuttle in such a way as to require the pins to be removed before the blocks or elements could be replaced, the removal of the pins frequently disfiguring the shuttle and enlarging the holes through which the pins pass. In the form of the invention already described when it is necessary to replace one of the tension elements the screw

34 is removed, after which the base 31 can be moved vertically until the tension device is outside the chamber 15, after which the blocks can be renewed and the device reinserted and held in place by the screw 34. Slot 30 prevents angular motion of the base 31 so that the pins 35 are always correctly positioned. It will be noticed that when screw 34 is removed the forward pressure 10 of the spring 20 will serve to hold the parts in place against wall 14 this feature of the invention permitting the operator to remove the screw 34 without disturbing the setting of the tension device. It will further be 15 noticed that should the base 31 and the blocks 36 and 37 slip when they are being removed the spring 20 will serve to throw them forwardly away from the loom.

In the modified form of the invention 20 shown in Figs. 5 and 6 the rear face of the front wall of the shuttle is formed as usual with no transverse slot but there is projecting rearwardly therefrom a pin 40 which is received by a small slot 41 formed in 25 one end of carrier 42 to prevent rotation of the carrier. The carrier 42 and parts associated therewith are in all other respects similar to those shown in the preferred form of the invention.

30 From the foregoing it will be seen that I have provided a very simple means for mounting the friction blocks of a narrow ware shuttle in such a way as to permit their renewal without disfiguring the shuttle. It 35 will also be seen that the weft is engaged by porcelain surfaces and is guided between the pins 35 which serve also to position the spring 20 the slots either in the shuttle or in the base of the tension device permitting 40 the latter to be moved transversely until properly positioned. Furthermore, it will be seen that the arrangement is such as to permit convenient removal of the parts in such a way that should they slip from the operator's hand they will be thrown forwardly.

Having thus described my invention it will be apparent that changes and modifications may be made therein by those skilled in the art without departing from the spirit 50 and scope of the invention and I do not wish to be limited to the details herein disclosed, but what I claim is:

1. In a loom shuttle, a pair of guide eyes,

friction blocks located between the eyes, yielding means to hold said blocks together 55 to exert friction tension on the yarn, supporting structure for the friction blocks, and means to hold said structure detachably to the shuttle, said structure being removable in a direction transverse of the weft and 60 guided in a transverse slot formed in the shuttle, said slot determining the angular position of the guiding means and said structure.

2. In a shuttle for looms, guide means for 65 the yarn, relatively movable blocks between which the yarn extends, yielding means to hold said blocks together, supporting structure for said blocks including spaced guides for the yielding means between which the 70 yielding means extends, and means for detachably securing the structure to the shuttle.

3. In a shuttle for looms, friction blocks for the yarn, a pair of spaced guides for 75 the blocks, a tension spring mounted on the shuttle and extending between the guides, a base to which the guides are secured, and detachable means for securing the base to the shuttle, said spring holding the friction blocks and the base against the shuttle when 80 said means are removed.

4. In a shuttle for looms, friction blocks for the yarn, a pair of spaced guides for the blocks, a tension spring mounted on the 85 shuttle and extending between the guides, a base to which the guides are secured, and detachable means for securing the base to the shuttle said spring holding the friction blocks and the base against the shuttle when 90 said means are removed and tending to move said blocks and base toward the front of the shuttle.

5. In a shuttle for looms, friction blocks for the yarn, a resilient device to hold the blocks together, a pair of spaced guide pins 95 for the blocks and device extending across a chamber formed in the shuttle to a point adjacent one boundary of the chamber to prevent accidental removal of the blocks, a base to which the pins are secured, and removable means for securing said base to the shuttle on the side of the chamber opposite the ends of the guide pins.

In testimony whereof I have hereunto affixed my signature.

PETER A. CARLSON.
